[57] **ABSTRACT**

A portable tool permitting, as desired, either selective plugging in of a printed-circuit module into one of a plurality of bottom grooves formed in a rack and above which groove the module is restrained by lateral slideways, or selective unplugging of one of the modules plugged into the bottom rack grooves. It comprises a grip formed by two elements movable relatively to each other. One of these elements is provided with a pair of claws adapted to engage lateral recesses in the rack when the operator moves the two grip elements toward each other. The other element is provided on the one hand, with pushing rods acting on the module to be plugged and, on the other hand, with hooks acting on the module to be unplugged, after having turned the grip the other way round.

FIG. 8

TOOLS FOR PLUGGING IN AND UNPLUGGING SUBSYSTEMS CARRIED ON SLIDEWAYS

The use of equipment for testing or controlling the electro-mechanical circuits to be found in systems of all kinds employed in the various spheres of modern activity has resulted in the introduction of cabinets of by no means negligible size, equipped with slide-in units or racks containing the equipment designed to perform the required functions.

In order, on the one hand, to reduce the number and size of such individual items and hence the cost of each installation and, on the other, to simplify the equipment handling operations inherent in the performance of each operation, it has been necessary to devise modules corresponding to specific circuits. These modules, which are made of insulating material, carry printed circuits and provide the requisite electronic components, are removably and interchangeably inserted into slideway systems with which the above-mentioned racks are equipped and, by their very association, provide the circuits needed for performing the required operation.

Experience has shown that notwithstanding these slideways the insertion or withdrawal of each such module, into and from the various racks, represents a very delicate manual operation by reason of the very small gaps existing between consecutive modules, which gap must nonetheless permit insertion or withdrawal of each module in addition to accommodating the various components equipping the printed circuits and which bulk to a considerable extent due to the presence of transistors, capacitors, resistors and so forth.

In view of these difficulties and in order to avoid damage to the modules, their circuits and their equipment as the result of inadvertent clumsiness when inserting or withdrawing the modules, the need arose to design and develop a device for plugging in or unplugging these modules.

During insertion, each module is introduced manually along the side rails provided in the rack. On the other hand, the final operation of plugging in, i.e., of engaging it into the bottom groove, is much trickier because it involves exerting a considerable force uniformly distributed over the upper edge of the module in order to ensure correct engagement. This delicate operation can be accomplished in outstandingly simple, efficient and reliable fashion by means of the device specifically designed for the purpose and which forms the object of the present invention.

This device is designed to make it possible to perform the reverse operation of selectively withdrawing modules one by one. Previously, this unplugging operation also required the application of a force, this time in the opposite direction, and which, again in order to avoid damaging the equipment, is uniformly distributed over the entire periphery of the module and is directed rigorously along the plane of symmetry of withdrawal of each module.

In other words the present invention relates to a simple, easy to handle device, requiring no special precautions in use, which, by being merely applied against the rack level with the corresponding rails, makes it possible to plug in or unplug the required modules by insert-

ing a uniformly distributed compressive or pulling force directed along the centerplane of said modules. The subject device of this invention avoids damage to the modules as a result of accidental mishandling when inserting or withdrawing them, thereby endowing them with great reliability notwithstanding the numerous manipulations to which they are subjected.

A portable device according to this invention is characterized by the fact that it comprises:

10 a grip consisting of two elements movable relatively to each other and normally kept spaced from each other by return springs;

15 two sets of movable arms pivotally mounted at either end of one of the grip elements and capable, in their resting positions, of penetrating into the rack on either side of the module to be plugged in, which arms comprise claws adapted to engage into recesses provided for the purpose in the lateral walls of the rack;

20 two actuating systems of the cam type which, when the operator moves the two grip elements toward each other, is effective in initially fetching the movable arms into a position wherein their claws engage into the anchoring recesses, and thereafter in exerting a pressure uniformly distributed over the upper edge of the module whereby to cause the same to engage into the bottom groove;

25 30 two extraction hooks fixed to either end of the second grip element and which, after the operator has turned the grip the other way round, enable him to engage them into holes provided for the purpose in the module to be unplugged and to thereafter withdraw the same by moving the two grip elements toward each other, during which operation the grip reacts against

35 the edges of the rack through two abutments fast with the grip element provided with the claw-bearing movable arms.

The description which follows with reference to the accompanying non-limitative exemplary drawings will give a clear understanding of how the invention can be carried into practice.

In the drawings:

45 FIG. 1 is a perspective showing of a device according to this invention, portrayed in the position in which it must be grasped in order to plug a module into a rack;

FIG. 2 is an end view of FIG. 1;

FIG. 3 is a side elevation view with partial cutaway;

50 FIG. 4 is a detail view on an enlarged scale showing the fastening claw actuating mechanism of the device in sectional side elevation;

FIG. 5 is a cross-section along the line V—V of FIG. 4;

55 FIG. 6 is an explanatory illustration of the manner of operation of the device, as used for plugging a module into a rack;

FIG. 7 is a cross-section taken along the line VII—VII of FIG. 6;

60 FIG. 8 is an explanatory illustration of the manner of operation of the device, as used for withdrawing a module from a rack; and FIG. 9 is a cross-section taken along the line IX—IX of FIG. 8.

The device shown for exemplary purposes in the drawings may be likened in general shape to a spring-type dumb-bell in that it is formed by a two-part grip, namely of two parallel cylinders 1_A, 1_B which can be gripped in one hand and tightened together against

countering springs 2_A , 2_B . These springs are carried on two end posts 3_A , 3_B which likewise form guides for the motion of element 1_B relatively to element 1_A . The posts 3_A , 3_B accordingly have one of their ends fixed into the corresponding ends of element 1_A , as is clearly shown at 4 in FIG. 3, while the other element 1_B is provided with bushes 5 through which the associated posts slide. The latter protrude through element 1_B and their outer ends are fitted with caps 6_A , 6_B the functions of which will be explained in greater detail hereinafter. Adjacent its ends, movable element 1_B is provided with rods 7_A , 7_B whose respective axes XX_1 and YY_1 lie in the vertical symmetry plane PP_1 of the device, which plane is shown in a dot-dash line in FIG. 2. The rods 7_A , 7_B have tapering terminal portions 8_A , 8_B which are curved to form extraction hooks 9_A , 9_B . It is important to note, as is clearly shown in FIGS. 1 and 9, that the tapering portions 8_A , 8_B are curved in such manner as to cause the pulling force exerted by the hooks to lie in symmetry plane PP_1 .

Adjacent to the ends of element 1_B are fixed the bases of cylindrical rods 10_A , 10_B extending through element 1_A , being guided therethrough by bushes such as the bush 11 shown in FIG. 3. The unrestrained ends of rods 10_A , 10_B , which protrude from element 1_A , respectively comprise, from top to bottom in FIG. 3, downwardly tapering frusto-conical portions 12_A , 12_B , cylindrical portions 13_A , 13_B of smaller diameter than cylindrical portion 10_A , 10_B , and transverse thrust plates 14_A , 14_B to the functions of which further reference will be made when the manner of operation of the device is described. The two ends of element 1_A comprise heads 15_A , 15_B , of rectangular shape for example and larger in size than the middle cylindrical portion 1_A , whereby to accommodate therein the upper portion of the anchoring claw assembly which will now be described with particular reference to FIG. 3 and to the two detail FIGS. 4 and 5.

Each head 15_A , 15_B comprises two lateral slots 16_A , 17_A (or 16_B , 17_B) which extend right through it. Accommodated in these slots and capable of swinging motion are the upper ends 18_A , 19_A of arms 20_A , 21_A and 20_B , 21_B fulcrumed on pivots 22_A , 23_A . Springs 24 positioned respectively in said slots continuously urge the pivotal arms 20_A , 21_A , 20_B , 21_B toward the protruding portion of the associated rods 10_A , 10_B , whereby to cause them to bear against the respective thrust plates 14_A , 14_B . The lower ends of arms 20_A , 21_A , 20_B , 21_B are provided with outwardly turned fastening claws 24_A , 25_A , 24_B , 25_B to which further reference will be made when the manner of operation of the device is described.

Between the lateral arms 20_A and 21_A is disposed a transverse camming plate 26 provided with two arms 27_A , 28_A engaged into said slots 16_A , 17_A and capable of swinging motion therein about the pivots 22_A , 23_A . Adjacent its upper central portion, plate 26 is provided with a cylindrical rivet 27 the head of which normally registers in contact with the joint between frusto-conical portion 12_A and the smaller-diameter cylindrical portion 13_A of guide 10_A . Further, fixed to plate 26, beneath rivet 27, is a transverse spring blade 28 the ends of which engage in corresponding recesses 29_A , 30_A formed in claw-arms 20_A , 21_A (see FIGS. 4 and 5). Spring blade 28 is secured by a screw 31 and an appropriately arcuate second spring blade 32.

It will already be manifest that, through the agency of spring blades 28 and 32, any pivotal motion of plate 26 about its hinge axis will cause the claw-arms 20_A , 21_A to pivot in the same direction against the countering return springs 24, and that, if for any reason one of the claw-arms should butt against an obstacle preventing it from pivoting, the three other claw-arms of the device are themselves nevertheless able to pivot.

Particular reference will now be had to FIGS. 4, 5, 6 and 7 for a description of the device in its function of ensuring perfect insertion of a module into a rack.

In FIGS. 6 and 7 a rack generally designated by reference numeral 33 is schematically illustrated in cross-section and longitudinal section respectively.

Along the side walls 33_A , 33_B of rack 33 are provided uniformly spaced vertical slideways 34_{A1} , 34_{B1} ; 34_{A3} , 34_{B3} ; 34_{A5} , 34_{B5} ..., while in the rack bottom 33_C are formed transverse grooves 35_{A1} , 35_{A3} , 35_{A5} ... which interconnect these slideways in pairs.

Further, formed in side walls 33_A and 33_B are two horizontal grooves 36_A , 36_B for receiving the claws of the movable arms of the device and for providing fastening points therefor, as will be explained in greater detail hereinbelow.

Each combination of two vertical slideways and the associated bottom groove can receive a board or module equipped with its printed circuit, such as 37_{A1} , 37_{A3} , 37_{A5} ...

Obviously, constant spacing between consecutive modules is so determined that, once the modules are in position, their printed circuits should connect with one another and also so that it be possible for a claw-arm to penetrate therebetween to a sufficient distance for its claw to register with the corresponding fastening groove.

When a new module such as module 37_{A3} is to be inserted, it is first inserted manually into the vertical slideways reserved for the purpose (in this case the slideway 34_{A3} , 34_{B3}). Module 37_{A3} will then be in the position shown in solid lines in FIGS. 6 and 7. At this stage recourse is had to the subject device of this invention for the final delicate operation of plugging in the module, that is to say of inserting it into the bottom groove 35_{A3} .

To that end the device is grasped in one hand and fetched into the position shown in solid lines in FIG. 6. This is accomplished by inserting movable arms 20_A , 20_B and 21_A , 21_B between modules 37_{A1} , 37_{A3} and 37_{A5} , 37_{A5} respectively, until the lower edges of camming plates 26 bear against the upper edge of the module 37_{A3} to be plugged in, the centerplane of which will then lie in the centerplane PP_1 of the device.

Upper element 1_B is then pressed toward element 1_A . During the initial stage of the descent of rods 10_A , 10_B , it will be seen that frusto-conical portions 12_A , 12_B will coact with the rivet heads 27 to thrust the corresponding plates 26 outwardly. Through the agency of spring blades 28 and 32, the plates 26 accordingly thrust arms 20_A , 21_A and 20_B , 21_B outwardly, thereby causing the claws 24_A , 25_A and 24_B , 25_B to engage in the corresponding horizontal grooves 36_A , 36_B which accordingly serve as fastening points. As element 1_B continues to be squeezed toward element 1_A against countering springs 2_A and 2_B , thrust blades 14_A and 14_B on rods 10_A and 10_B then exert, against the upper edge of module 37_{A3} , a symmetrical downward thrust since

the device is locked in position by the claws engaged in the horizontal grooves. Responsively to his uniformly distributed and vertically centered force, module 37_{A3} is plugged into the lower groove 35_{A3}, being uniformly nested therein in parallelism with the centerplane of the module. The various component parts of the device are then in the final configuration shown in dotted lines in FIG. 6.

Once the module has been plugged in, the pressure on element 1_B can be released to allow the latter to be raised by the return springs 2_A and 2_B and the frusto-conical portions 12_A, 12_B of rods 10_A and 10_B to retract. The four claws 24_A, 25_A and 24_B, 25_B then revert to their initial resting positions and the device can be withdrawn from the rack.

As indicated precedingly, it should be noted that by virtue of the elastic actuation of the claw-arms, it is possible for one of these arms to remain retracted while the others move into their fastening positions if, for instance, that arm were to be hindered in its movement toward the fastening groove by possibly bulky and projecting components like potentiometers, capacitors, resistors, transistors, and the like, carried on certain modules. In that event the claw-arm in question will remain retracted without preventing plugging in from being effected by means of the other three claw-arms.

The device will now be described in connection with its use for withdrawing a module from a rack, with particular reference to FIGS. 8 and 9.

In order to avoid an unnecessarily lengthy description, the description of the arrangement of the modules in rack 33 will not be repeated, and it should merely be noted that in this case all the modules 33_{A1}, 33_{A3}, 33_{A5} .... are fully inserted into the corresponding bottom grooves 35_{A1}, 35_{A3}, 35_{A5}.

In order to unplug one of the modules, for example module 37_{A3}, the device is grasped in one hand, but this time the other way round, that is to say with element 1_A upwards. The two ends 9_A and 9_B of extraction hooks 8_A and 8_B are then inserted into extraction holes 38_A, 38_B provided for the purpose along the edge of each module.

The two elements 1_A and 1_B of the device are then squeezed together, and the initial effect of this is to cause the two caps 6_A, 6_B to contact the upper face of the side walls 33_A and 33_B of the rack, which walls accordingly serve as reaction points for the device. If the two elements 1_A and 1_B continue to be squeezed together, lower element 1_B will move toward upper element 1_A, thereby causing module 37_{A3} to be withdrawn from bottom groove 35_{A3} and to be fetched into the position shown in dotted lines in FIG. 8. As explained precedingly, by virtue of the curved shape of extraction hooks 8_A, 8_B, module 37_{A3} is withdrawn along the centerplane PP₁ of the device and consequently along the centerplane of the module. After the latter has been extracted from bottom groove 35_{A3} it can easily be removed from lateral slideways 34_{A3}, 34_{B3} and then detached from hook ends 9_A and 9_B.

An alternative module corresponding to the new program required can then be plugged in, in the manner described hereinabove with reference to FIGS. 6 and 7.

It goes without saying that many changes and substitutions may be made in the embodiment described for exemplary purposes hereinbefore, without depart-

ing from the scope of the invention as set forth in the appended claims.

I claim:

1. A portable device permitting, as desired, either selective plugging in of a printed-circuit module into one of a plurality of bottom grooves formed in a rack and above which groove the module is restrained by lateral slideways, or selective unplugging of one of the modules plugged into the bottom rack grooves, said device comprising:

a grip formed by two elements movable relatively to each other and normally held in mutually spaced relationship by return springs;

two sets of movable arms pivotally mounted at either end of one of the grip elements;

said movable arms being capable, in their resting position, of penetrating into the rack and being provided with claws capable of engaging into lateral recesses provided for the purpose in the side walls of the rack;

two cam type actuating means so devised that when the operator moves the two grip elements toward each other they initially cause said movable arms to move into a position wherein their claws engage in said lateral recesses, and thereafter exert a pressure uniformly distributed over the upper edge of said module to be plugged in whereby to plug the same into the bottom groove;

and two extraction hooks fixed to either end of the other grip element;

said hooks being so devised as to enable the operator, after he has turned the grip the other way round, to engage them into holes provided for the purpose in the module to be extracted and to thereafter unplug the same by squeezing the two grip elements together, said grip then reacting against the edges of the rack through the medium of two abutment members fast with that grip element which supports said movable claw-arms.

2. A device for plugging in and unplugging printed-circuit modules, as claimed in claim 1, wherein the movable claw-arms of each set thereof are independent of each other in that they are urged toward their respective resting positions by individual return springs and toward their fastening positions through the agency of a common transverse spring blade rigid with a central member which is hingedly mounted on a pivot common to the movable claw-arms and which is itself subjected to the direct action of the corresponding cam type actuating means.

3. A device for plugging in and unplugging printed-circuit modules, as claimed in claim 2, wherein each cam type actuating means is formed by a rod of which one end is fixed to that grip element which carries the two extraction hooks, said rod extending through the other grip element and having, protruding therefrom, firstly a frusto-conical camming portion which coacts with an abutment fast with the central member hingedly mounted between the movable claw-arms, and secondly a cylindrical portion provided on its free end with a thrust plate which, when the operator squeezes the two grip elements together, bears against the upper edge of the module to be plugged in.

4. A device for plugging in and unplugging printed-circuit modules, as claimed in claim 1, wherein the

hooks on the extraction members are offset in such manner that the pull exerted by said extraction members be directed along the then coplanar centerplanes of the module to be unplugged and of the device itself, respectively.

5. A device for plugging in and unplugging printed-circuit modules, as claimed in claim 1, wherein the return springs which urge the two grip elements away from each other are coil springs which surround posts

supported on either end of the grip, said posts having one of their ends fixed to that grip element which carries the movable claw-arms, extending through the other grip element the motion of which they serve to guide, and being extended by cap-forming members designed to react against the rack when the operator uses the device for unplugging a module.
